UNITED STATES PATENT OFFICE.

EDWARD ARTHUR BARNES, OF GIANT, CALIFORNIA.

NITRATED PRODUCT AND PROCESS OF MAKING SAME.

1,273,568.

Specification of Letters Patent. Patented July 23, 1918.

No Drawing.

Application filed October 11, 1915. Serial No. 55,329.

To all whom it may concern:

Be it known that I, EDWARD A. BARNES, a subject of the King of England, residing at Giant, in the county of Contra Costa and 5 State of California, have invented new and useful Improvements in Nitrated Products and Processes of Making Same, of which the following is a specification.

My invention relates to the separation and 10 isolation of various constituents found in natural petroleum oils; and its object is to obtain the aromatic (benzenoid) hydrocarbons in a directly usable form as mono-nitro-derivatives which, by further treatment, may be obtained in a form fit for commercial use.

The natural petroleum oils, from whatever field they are derived, are known to contain a considerable percentage of aromatic, and other unsaturated cyclic, hydrocarbons, and these compounds greatly detract from the value of the finished products and also adversely affect the yield of the lighter and more valuable fractions.

Under ordinary methods of refining, these 25 compounds are broken up by the action of fuming sulfuric acid (oleum) at moderate temperatures and pressures; being converted into soluble sulfonates. No great attempt has been made to recover them on a 30 commercial scale from waste acids obtained in such treatment, owing to the difficulties of handling so large quantities of acid sludge.

In my invention I obtain the above aromatic hydrocarbons in a directly usable form as mono-nitro-derivatives, which can be fractionally distilled so as to separate the various mono-nitro-derivatives, which are 40 thus obtained in a form fit for commercial use in the manufacture of anilin dyes and explosives.

As a rule the crude oils or distillates which are to be treated contain a preponderance of saturated hydrocarbons and a smaller amount of benzenoid hydrocarbons. When dealing with crude oils, a preliminary distillation is necessary to free them from excessive impurities, but the resulting distillates merely require agitating with cold sulfuric acid to remove the unsaturated hydrocarbons. The percentage of sulfuric acid depends on the quantity of these impurities and repeated agitation of the distillates with 1½% to 2% of their volume, of 55 96% sulfuric acid is given until no further

discoloration is produced and shrinkage of the bulk of the distillate ceases.

This cleaned distillate is then nitrated with a mixture of nitric acid and sulfuric acid at as low a temperature as possible, when the whole of the aromatic hydrocarbons is obtained as mono-nitro-derivatives.

I take a mixture of 625 grams of nitric acid 70% and 325 grams of sulfuric acid 65 96%, and run this in a fine stream into about five thousand grams of cleaned distillate contained in a vessel provided with a stirring device and cooling coils. The temperature is kept as low as possible and agitation 70 continued for four hours after the acid is in, when the contents are allowed to separate. Three layers are formed, the top one consisting of cleaned paraffin distillate, the second about $\frac{1}{10}$ the bulk of the first consisting of nitro-aromatic hydrocarbons, and the third of waste acids.

These latter should not contain more than $\frac{1}{2}\%$ of unused nitric acid, and excess will 75 show that too great a proportion of mixed acid was used and work is regulated on this basis. Considerable variation may be allowed in proportion and strength of mixed acid, but the one given is found sufficiently strong to serve its purpose economically.

These nitrated compounds separate cleanly 80 forming an intermediate layer between the acid and the distillate, which latter is obtained in a much purer state than that obtained by "oleum" treatment. The mixture 85 of nitro-aromatic hydrocarbons which represents 10% to 15% of the original amount of distillate, dependent on the oil field from which it was derived, can be fractionally separated in any suitable apparatus, and 90 these fractions severally reduced to their corresponding amido-derivatives and used as such in the manufacture of anilin dyes.

Further, I find that the complex mixture 100 of mono-nitro-derivatives obtained in this treatment of crude oils and distillates has the property of dissolving in nitroglycerin and considerably reducing its freezing point, and that this property is also possessed by the mixture of di-nitro-derivatives obtained 105 by re-nitrating the mixture of mono-nitro-derivatives with stronger acids at a higher temperature, and again possessed by the mixture of tri-nitro-derivatives obtained by re-nitrating the mixture of di-nitro-derivatives with still stronger acids at still higher 110 temperatures, and that all of these mixtures

which range from liquids to solids are extremely suitable for employment in the manufacture of low freezing explosives.

The mixed acid I employ for renitrating the mixture of mono-nitro-derivatives has a composition of 36% of HNO_3 ; 62% of H_2SO_4 and 2% of OH_2 , and the temperature of reaction is maintained at 75° centigrade.

The mixed acid I employ for renitrating the mixture of di-nitro-derivatives is the strongest attainable, made by mixing 93% of HNO_3 with "oleum" containing 20% or more of SO_3 , and the temperature of the reaction is maintained between 100° and 125° centigrade. Variations in all these mixtures is allowable but are not economical.

Having thus described my invention, what I claim and desire to secure by Letters Patent is—

1. The process which comprises gradually adding a mixture of nitric and sulfuric acids, while stirring and cooling, to petroleum distillates containing a preponderance of saturated hydrocarbons and a smaller amount of benzenoid hydrocarbons, and separating from the oil and waste acid the nitro-derivatives thus formed.

2. The process which comprises converting into their mono-nitro-derivatives the benzenoid hydrocarbons in petroleum distillates containing a preponderance of saturated hydrocarbons and a smaller amount of benzenoid hydrocarbons by treating the oil at a low temperature with suitable proportions of a mixture of nitric and sulfuric acids, and separating the mixture of nitro-derivatives from the remaining oil.

Copies of this patent may be obtained for five cents each, by addressing the "Commissioner of Patents, Washington, D. C."

3. The process of treating a partly purified petroleum distillate containing saturated hydrocarbons and a smaller amount of benzenoid hydrocarbons and obtainable by distilling crude petroleum to separate as a residue certain impurities, agitating the distillate with a small proportion of sulfuric acid, allowing the mixture to settle and removing the waste acid with impurities of the distillate contained therein, which comprises gradually adding a mixture of nitric and sulfuric acids containing a small proportion of water to the purified distillate while stirring and cooling the same, allowing the mixture to settle into distinct strata comprising respectively paraffin hydrocarbons, nitro-benzenoid hydrocarbons and waste acids, and separating said nitro-benzenoid hydrocarbons.

4. The process which comprises treating at a low temperature petroleum oils containing saturated hydrocarbons and a smaller amount of benzenoid hydrocarbons with a mild nitrating agent comprising nitric acid, sulfuric acid and water to convert benzenoid hydrocarbons in the oil mainly into their mono-nitro-derivatives, separating the nitro-derivatives and treating them with a stronger nitrating agent at a higher temperature to produce polynitro-derivatives of said benzenoid hydrocarbons.

In testimony whereof I have hereunto set my hand in the presence of two subscribing witnesses.

EDWARD ARTHUR BARNES.
